WO 2005084243 A2 9/2005
WO 2012156674 A1 11/2012*Primary Examiner* — Deanna L Pratt*Assistant Examiner* — Katie Mroczka(74) *Attorney, Agent, or Firm* — Holland & Hart, LLP(57) **CLAIM**

The ornamental design for an animal treat, as shown and described.

DESCRIPTION

FIG. 1 is a perspective view of an embodiment of an animal treat, showing my new design.

FIG. 2 is a top view of the design illustrated in FIG. 5, the bottom view being a mirror image thereof;

FIG. 3 is a left end view of the design illustrated in FIG. 5, the right end view being a mirror image thereof;

FIG. 4 is a front view of the design illustrated in FIG. 5, the rear view being a mirror image thereof;

FIG. 5 is a perspective view of another embodiment of an animal treat, showing my new design;

FIG. 6 is a top view of the design illustrated in FIG. 4, the bottom view being a mirror image thereof;

FIG. 7 is a left end view of the design illustrated in FIG. 4, the right end view being a mirror image thereof; and,

FIG. 8 is a front view of the design illustrated in FIG. 4, the rear view being a mirror image thereof.

The broken lines in the drawings are for the purpose of illustrating unclaimed portions of the animal treat and form no part of the claimed design.

1 Claim, 4 Drawing Sheets(56)
